WASHER FOR A MILKING SYSTEM

Lloyd F. Bender, Hayward, Wis.

Filed June 16, 1960, Ser. No. 60,997

Term of patent 14 years

(Cl. D49—1)

Fig. 1 is a perspective view of a washer for a milking system embodying my new design;

Fig. 2 is a top plan view thereof; and

Fig. 3 is a bottom plan view thereof.

I claim:

The ornamental design for a washer for a milking system, substantially as shown.
